UNITED STATES PATENT OFFICE.

WILLIAM W. HAWKINS, OF BROOKLYN, NEW YORK, ASSIGNOR TO WEBSTER ELECTRIC COMPANY, OF RACINE, WISCONSIN, A CORPORATION OF WISCONSIN.

IGNITION MAGNETO.

Application filed February 20, 1922. Serial No. 537,992.

This invention relates to magnetos of the type used for ignition purposes with internal combustion engines, and particularly to magnetos of the oscillator type.

5 The object of the present invention is the provision of a magneto and circuit connections therefor, by means of which a spark of high intensity will be produced.

In the drawings which disclose one specific 10 embodiment of the invention

Figure 1 is an end view of the device such as would be obtained by looking at Figure 3 from above;

Figure 2 shows a section through the device at one side of the magnet and pole pieces;

Figure 3 is a section substantially on the line 3—3 of Figure 2, looking in the direction of the arrows;

20 Figure 4 is a detached view of the magnet pole pieces and the inductor showing the inductor rotated to its cocked or set position, and

Figure 5 is a diagram schematically indicating the circuit connections.

In magnetos of the type herein disclosed, it is usual to provide means driven by moving parts of the engine or motor, by means of which the rotor shaft is moved to a cocked 30 or set position, and then tripped off, resilient means being provided to cause the rapid return of the rotor to its normal position after being tripped.

As the cocking and releasing means for magnetos of this type are exceedingly old and well known in the art, this part of the applicant's device has not been illustrated in the drawings and will not be described in the specification, it being understood that 40 any known or appropriate device of this character may be employed.

Referring now to the drawings in which like reference characters refer to similar parts throughout the several figures of the drawings, 10 indicates the usual permanent U-shaped or horseshoe magnet. In contact with the leg 11 of the magnet 10 is the pole piece consisting of the legs 12 and 13. In engagement with the leg 14 of the magnet 10 50 is a pole piece comprising the legs 15 and 16. Extending upwardly from the leg 16 is an arm 17 in engagement with which is the core piece 18. Wound about the core 18 is the primary coil 19 and the secondary coil 20 of a transformer. Positioned opposite the

pole piece 16 is an auxiliary pole piece 21 provided with an upwardly extending arm 22 in engagement with the end of the core 18 remote from the upright 17.

It is to be understood that the part 17, core 60 18 and parts 21 and 22 are all formed of magnetizable material, in the usual manner. It should also be noted that while the part 21 is located on the same side of the rotor as the legs 12 and 13, it is insulated from 65 the leg 11 of magnet 10 but is magnetically joined to the leg 16 through the core piece 18.

The rotor shaft is shown at 23. Non-rotatably secured to the shaft 23, in any desired manner, is the inductor 24 formed of 70 the usual magnetizable material. It will be noted that one end of the inductor 24 is T-shaped so as to bridge the space between adjacent pole pieces 13 and 21.

Non-rotatably secured to the end of the 75 shaft 23, in any desired manner, as by the spline 25 and nut 26, is a yoke 27 provided with the oppositely extending arms 28. Each of the arms 28 is provided with an outwardly extending stud 29 which is arranged to 80 be encircled by one end of a retractile spring 30, by means of which the rotor shaft is returned to its normal position after the rotor has been cocked. The ends of the springs 30 remote from the studs 29 are joined to studs 85 31' projecting outwardly from the frame of the magneto.

Secured to the end of the shaft 23 remote from the yoke 27 is a collar 31 provided with an outwardly extending arm 32. Pivoted 90 to the arm 32 by means of the pivot 33 is the contact actuating dog 34. Secured to the collar 31, as by the screws 35, is a spring 36 which engages the inner end of the dog 34 and tends to normally maintain the 95 dog in the position indicated in Figure 5. Rigidly supported by the screws 37 and having its free end projecting into the path of the dog 34 is a bow spring 38. Pivoted 100 mounted on the screw 39 is the arm 40 which is joined to the spring 38 by the screw 41. The arm 40 at its end remote from the pivot 39 is provided with a contact 42 which is adapted to engage the fixed contact 43 of the interrupter adjustably mounted in the clip 44. 105

Wound about the pole piece legs 13 and 15 are the coils 45 and 46, respectively. The coils 45 and 46 are in a closed circuit including the condenser 47. One side of the condenser 47 is permanently connected to 110

ground at 48. The other side of the condenser is connected to ground through the interrupter contacts 42 and 43, arm 40, and supporting screw 39 which enters the metallic portion or frame of the device.

One end of the primary coil 19 is grounded, and the other end of the coil is connected to the conductor 49, which joins the condenser to the end of the coil 46 remote from coil 45. The secondary coil 20 is grounded at one end, the other being connected to a distributor, spark plug, or any desired device.

Having now described the arrangement of the several parts of my invention, the operation will now be described.

In following the operation, it should be kept in mind that the interrupter operating mechanism shown in Figures 1 and 5 is viewed from the opposite direction to that of the rotor as viewed in Figures 2 and 4. In other words, when read on the drawings, when the rotor shaft of Figures 2 and 4 rotates in a clockwise direction, the shaft and interrupter operating mechanism of Figures 1 and 5 will be rotated in a counterclockwise direction, due to the fact that they are viewed from an opposite direction.

In the operation of the device, the rotor armature 24 will be moved to cocked or set position as indicated in Figure 4. At this time, the flux or magnetic lines will pass from the leg 16 to the leg 12 of the pole pieces, and the coil bearing legs 13 and 15 will be short circuited so no magnetic lines will pass through the coils 45 and 46. Upon release of the rotor, the armature will take up a position substantially as indicated in Figure 2.

The rotor will be cocked by moving the armature 24 in a clockwise direction, as viewed in Figure 4. This movement of the rotor shaft will result in moving the interrupter arm 32 in a counterclockwise direction, as viewed in Figures 1 and 5. During this counter-clockwise movement of the arm 32, the outer end of the dog 34 will engage the free end of the bow spring 38 and will be rotated about its pivot pin 33 against the tension of spring 36. Just before the rotor reaches its fully cocked position, the dog 34 will ride off from the end of the spring 38 and will be moved so as to extend radially from the shaft 23. The dog 34 will at this time be spaced a very short distance from the end of the bow spring 38.

Upon the beginning of the return movement of the rotor, the dog 34 will engage the end of spring 38, moving contact 42 into engagement with contact 43. Contacts 42 and 43 will be held firmly in engagement by the resiliency in the free end of the spring 38 until the rotor shaft reaches substantially the position indicated in Figure 2, at which time the dog will slip off from the end of

the spring 38 and permit the resiliency of the spring 38 to open the contacts 42 and 43.

During the return movement of the rotor in a counter-clockwise direction, the flux or magnetic lines passing through the pole piece legs 13 and 15 will change very rapidly, thus setting up an electrical impulse in the windings 45 and 46. Due to the fact that the interrupter contacts are in engagement at this time, the first part of this impulse will pass from ground 48, through the coils 45 and 46 in series, and through the interrupter contacts back to ground.

However, when the contacts 42 and 43 open as the rotor approaches the position indicated in Figure 2, the path to ground through the interrupter contacts is opened, and the current must now flow to ground through the coil 19. Thus, an impulse of current is sent through the coil 19, which is augmented by the discharge from the condenser 47, and is further augmented by the flux or magnetic lines which are now flowing through the core 18 due to the fact that the T-headed end of the rotor armature 24 is now bridging the space between the auxiliary pole piece 21 and the pole piece leg 13.

It will be recalled that the auxiliary pole piece 21 is merely an extension of the pole piece 16, so the magnetic lines will now extend from the leg 14 of the magnet 10, through pole piece 16, arm 17, core 18, arm 22, auxiliary pole piece 21, the head of the rotor 24, and pole piece leg 13, to the other leg 11 of magnet 10. The surge of current through coil 19 brought about by the conditions above described produces a high potential impulse in the secondary winding 20 which will be effective to produce a spark of great intensity.

While in the above description but a single form of applicant's device is disclosed, it is to be understood that many modifications in the specific details are contemplated and the invention, therefore, should be limited merely by the scope of the appended claims.

What I claim is new and desire to secure by Letters Patent of the United States is:

1. In a magneto, a generating winding, a transformer comprising a primary coil and a secondary coil, one end of said generating winding being connected to one end of said primary coil, the opposite end of said generating winding being grounded and the opposite end of said primary coil being grounded, a bridge connected at one end to the point of connection between said generating winding and said primary coil and the other end being connected to ground, and an interrupter in said bridge circuit, said secondary coil being connected at one end to the grounded end of said primary coil and at the other end being connected to the spark plug of the ignition system.

2. In a magneto, a pole piece, a generat-

- ing winding thereon, a transformer including a core and a coil thereon, means for creating a magnetic field, and a rotor arranged to first complete a path for the flow of magnetic lines or flux through said pole piece for energizing said generating winding and to subsequently complete a path for the flow of flux through said core and pole piece in series for energizing said transformer 10 coil.
3. In a magneto, a pole piece, a generating winding thereon, a transformer including a core and a coil thereon, means for creating a magnetic field, one end of said 15 transformer core being magnetically separated from said magnetic field, a rotor, and means for causing an oscillating movement of said rotor, said rotor being arranged to complete a path for the flow of magnetic 20 lines or flux through said pole piece during its initial operative movement and to subsequently complete a path for the flow of flux through said core and pole piece in series.
4. In a magneto, a magnet, a pair of pole pieces therefor, generating windings thereon respectively, a transformer including a core and a coil thereon, said core having a magnetically isolated end, a rotor arranged 30 to complete a path for the flow of magnetic lines or flux through said pole pieces during its initial operative movement and to subsequently complete a path for the flow of flux through the magnetically isolated 35 end of said core and one of said pole pieces in series.
5. In a magneto, a magnet, a pair of pole pieces therefor, generating windings thereon respectively, a transformer including a core having one end separated from said 40 pole pieces and a coil on said core, a rotor, and means for causing an oscillating movement of said rotor, said rotor being arranged to complete a path for the flow of magnetic 45 lines or flux through said pole pieces during its initial operative movement and to subsequently complete a path for the flow of flux through said core and one of said pole pieces in series.
6. In a magneto, a pole piece, a generating winding thereon, a transformer including a core, a coil on said core, means for creating a magnetic field, a rotor arranged to first complete a path for the flow of magnetic 55 lines or flux through said pole piece and to subsequently complete a path for the flow of flux through said core and pole piece in series, a circuit including said winding and said coil, a branch from said circuit between said coil and winding, and an interrupter in said branch.
7. In a magneto, a pole piece, a generating winding thereon, a transformer including a core, a coil on said core, means for creating a magnetic field, one end of said 60
- transformer core being magnetically separated from said magnetic field, a rotor arranged to first complete a path for the flow of magnetic lines or flux through said pole piece and to subsequently complete a path 70 for the flow of flux through said core and pole piece in series, a circuit including said winding and said coil, a branch from said circuit between said coil and winding, an interrupter in said branch, and a condenser 75 in parallel with said interrupter.
8. In a magneto, a magnet, a pair of pole pieces therefor, generating windings on said pole pieces respectively, a transformer including a core, a coil on said core, a rotor 80 arranged to first complete a path for the flow of magnetic lines or flux through said pole pieces and to subsequently complete a path for the flow of flux through said core and one of said pole pieces in series, a circuit 85 including said windings and said coil, a branch from said circuit between said coil and said windings, and an interrupter in said branch.
9. In a magneto, a magnet, a pair of pole pieces therefor, generating windings on said pole pieces respectively, a transformer including a core having a magnetically isolated end, a coil on said core, a rotor, means for causing an oscillating movement of said 90 rotor, said rotor being arranged to complete a path for the flow of magnetic lines or flux through said pole pieces during its initial operative movement and to subsequently complete a path for the flow of flux through 100 the magnetically isolated end of said core and one of said pole pieces in series, a circuit including said windings and said coil, a branch from said circuit between said coil and said windings, and an interrupter in 105 said branch.
10. In a magneto, a magnet, a pair of pole pieces therefor, generating windings on said pole pieces respectively, a transformer including a core, a coil on said core, a rotor, means for causing an oscillating movement of said rotor, said rotor being arranged to complete a path for the flow of magnetic lines or flux through said pole pieces during 110 its initial operative movement and to subsequently complete a path for the flow of flux through the core and one of said pole pieces in series, a circuit including said windings and said coil, a branch from said circuit between said coil and said windings, an interrupter in said branch, and a condenser in 120 parallel with said interrupter.
11. In a magneto, a magnet, pole pieces therefor, generating windings on said pole pieces respectively, a branch from one of said pole pieces terminating in an auxiliary pole piece adjacent to the other one of said pole pieces, and a rotor arranged in one position to complete a path for the flow of flux from one of said pole pieces to the other direct, 125 130

and in another position to complete a path from said auxiliary pole piece to the aforesaid other one of said pole pieces.

12. In a magneto, a magnet, pole pieces therefor, generating windings on said pole pieces respectively, a branch from one of said pole pieces, an auxiliary pole piece magnetically joined to said branch, said auxiliary pole piece being adjacent to the other one of said pole pieces, and a transformer having a coil wound about said branch.

13. In a magneto, a magnet, pole pieces therefor, generating windings on said pole pieces respectively, a branch from one of said pole pieces terminating in an auxiliary pole piece adjacent to the other one of said pole pieces, a rotor arranged in one position to complete a path for the flow of flux from one of said pole pieces to the other direct, and in another position to complete a path from said auxiliary pole piece to the said other one of said pole pieces, and a transformer having a primary coil wound about said branch.

25 14. In a magneto, a magnet, pole pieces therefor, generating windings on said pole pieces respectively, a branch from one of said pole pieces terminating in an auxiliary

30 pole piece, a rotor arranged in one position to complete a path for the flow of flux from one of said pole pieces to the other direct, and in another position to complete a path from said auxiliary pole piece to the said other one of said pole pieces, a circuit including 35 said windings and coil, a branch circuit extending from said circuit, and an interrupter in said branch circuit.

15. In a magneto, a magnet, pole pieces therefor, generating windings on said pole pieces respectively, a branch from one of 40 said pole pieces terminating in an auxiliary pole piece, a rotor arranged when in a substantially horizontal position to complete a path for the flow of flux from one of said pole pieces to the other direct, and when in 45 an inclined position to complete a path from said auxiliary pole piece to the said other one of said pole pieces, a circuit including said windings and coil, a branch circuit extending from said circuit between said coil 50 and said windings, and an interrupter in said branch circuit.

In witness whereof, I hereunto subscribe my name this 30th day of January, 1922.

WILLIAM W. HAWKINS.
